UNITED STATES PATENT OFFICE.

OTTO RACINE, OF DENISON, IOWA.

QUILTING-FRAME.

1,261,614.

Specification of Letters Patent. Patented Apr. 2, 1918.

Application filed May 22, 1917. Serial No. 170,269.

To all whom it may concern:

Be it known that I, OTTO RACINE, a citizen of the United States, residing at Denison, in the county of Crawford and State of Iowa, have invented new and useful Improvements in Quilting-Frames, of which the following is a specification.

This invention relates to furniture, and more especially to fabric stretchers; and the 10 object of the same is to produce a frame on which quilts, comforts, and the like may be made, or upon which curtains and other delicate fabrics can be stretched and dried.

The principal feature of the invention is 15 the means which are provided for readily changing the dimensions of the frame while yet retaining the possibility that the side bars may rotate on their trunnions in the end bars so that a quilt being made can be 20 roller or unrolled as is necessary and desirable.

Details will be found in the following specification, and reference is made to the accompanying drawings wherein:—

25 Figure 1 is a plan view of this complete frame in its considerably distended condition, with parts broken away and in section.

Fig. 2 is an end elevation, showing two 30 supporting legs, illustrating one of the trunnions at the outer extremity of its slot and the other trunnion adjusted inward of its slot.

Fig. 3 is a perspective detail of one side 35 bar and of certain of the sleeves adapted for use on the long trunnion thereof, one of them being in place and the others removed and turned to give different views; and this view also shows the extension member removed from the opposite trunnion.

40 Fig. 4 is a plan view of one end of the frame, showing two extensions on the trunnions outside the end bar and a supplemental cross bar mounted on the trunnions of the extensions.

45 Figs. 5 and 6 are enlarged detailed views of a sleeve, partly in section to show the manner in which the strips are attached thereto, and of an extension in section to show the preferred means of providing it with a 50 socket and a trunnion.

This frame is made up essentially of two end bars, detachable legs for supporting them when desired, two side bars having trunnions supported by the end bars and 55 means for adjusting the length of their bodies, such means including two extension

members which may be used inside the end bars or outside the same as preferred, and a supplemental cross bar much like one of the end bars and whose use will be explained. The several bars and parts thereof are preferably of wood, and clear lumber should be selected, free from knots and warps and well seasoned, and by preference treated finally with oil and perhaps varnished so that the wood will be protected from the elements and from the dampness of wet curtains that may be stretched thereon. Each side and end bar is made foldable so that the entire frame may be collapsed 60 into small compass, and by preference the outfit will include a casing in which it can be packed when not in use. For holding any two hinged parts distended I make use of a pivoted hook or catch or equivalent device, described herein only for purpose of illustration, and by preference this is located so that when it is in use it spans the hinge-line and is disposed on the proper side of the member to resist the strain of the 65 work held by the frame. The end bars will be about two by three inches and all other bars about two by two inches. Each end bar will be between seven and eight feet long, and each side bar the same without the 70 trunnions. The hinges, catches, and keys are preferably of metal.

Coming now to a detailed description of the parts as shown in the drawings, each end bar is made in two halves 1 and 2, standing end to end and hingedly connected with each other at 3 on their lower edges, one half carrying a hook 4 adapted to be extended across the point where their ends meet and to engage a pin 5 in the other half for holding these parts distended. Each half also carries on its outer face near its outer end a socket 6 into which may be inserted the upper end of a detachable and removable leg 7. Each half is longitudinally slotted 90 as at 8, the slots stopping well short of the ends of the half as seen, and a series of upright holes 9 is provided in this half, intersecting the slot and preferably marked on the upper edge of the end bar as perhaps 95 best seen in Fig. 1. It is into these holes that the keys 10 are subsequently inserted as will appear. There are two end bars, each composed of two parts which in the present case are halves, and each end bar 100 can be folded into a length of four feet or less.

Each side bar is likewise in two parts although these are not halves. The longer part 11 is connected with the shorter part 12 by a hinge 13, and a catch 14 engages a pin 15 and stands across the hinge line like the catch on the end bar described above. The long part is about four feet and the short part about eighteen inches in length. Projecting rigidly from the outer extremity 5 of the long part is a trunnion 16 of a size to pass through one of the slots 8, and at an appropriate point this trunnion is pierced with a transverse hole 17 adapted to align with any pair of holes 9 and to receive a 10 key. The outer end of the short part 12 is likewise provided with a trunnion 18 which is of considerable length, and this trunnion has through it several holes 19 disposed about eighteen inches apart and also adapted 15 for receiving a key in a manner which will be described below. With the parts thus far described, the end bars are supported by the legs and stand in parallelism, and the trunnions of the side bars are passed 20 through the slots in the end bars and held therein by keys engaging the perforations 25 9 and 17 or 9 and 19.

For extending the length of the body-portion of each side bar I provide a number of 30 sleeves, each of which is a block 20 about two by two inches and eighteen inches in length, and through its longitudinal axis is an opening 21 adapted to slip over the long trunnion 18. In one end of each sleeve is a 35 pair of pins 22 and similar pins are provided on the outer end of the short part 12. In the opposite end of each sleeve is a pair of sockets 23 adapted to be engaged by the pins of the contiguous sleeve or the short 40 part. Each sleeve carries a hook 24 and has at a proper point a pin 25 with which the hook of the adjacent sleeve engages like the hooks and pins on the end bars and side bars above described. With respect to these 45 hooks and the pins and sockets, the inner part 12, which also is about eighteen inches in length, may be considered as one of the sleeves; but the long trunnion 18 is rigidly connected with and carried by this inner 50 part, whereas the other blocks having openings 21 through them which slip over this trunnion, and the holes 19 are properly disposed to stand about six inches beyond the outer ends of the several blocks, no matter 55 how many are applied. Thus is provided means for increasing the length of the short portion of each side bar. Assuming that its two parts 11 and 12 measure about five and a quarter feet, if we add one sleeve or block 60 20 the length is increased to six feet and nine inches, and if we add two blocks the length is yet further increased to eight feet and a quarter, and so on. In any case, however, there is a projecting portion of the long 65 trunnion 18 which extends through the slot

8 in the adjacent end bar, and there is always a hole 19 which comes in alignment with the holes 9 in said end bar so that a key may be inserted.

For lengthening the side bars so that they 70 may be used with a quilt or a pair of curtains of extreme length, I make use of an extension in the shape of a block 30 about two inches by two inches and of any suitable length, the same having a socket 31 in one 75 end to pass over the tip of either trunnion and an axial trunnion 38 projecting rigidly from its other end and provided with a hole 39 for the reception of one of the keys. There may, in fact, be provided several of 80 these extension members with any outfit, and as seen in Fig. 4 they may be applied to the trunnions of the side bars outside the end bar, or of course they could be applied inside if preferred. In Fig. 4 is shown an additional cross bar made up of two halves 32 hinged together as at 33 and latched as at 34, each half being slotted and perforated like the half of one of the end bars. In fact, this additional member is in effect practically a duplicate of either of the end bars excepting that it need not be quite so heavy and need not have sockets for the legs. It may connect either of the trunnions of the side bars either inside the end bar or outside 95 the latter as seen in Fig. 4, and its principal use is to sustain and brace the side bars when the latter are lengthened as is necessary on occasions. There need be but one of these members, and it can fold within a 100 length of four feet.

To the upper face of all end bars and side bars and the sleeves and extensions of the latter, and adjacent one edge of said face, are attached fabric strips 40; while metallic 105 strips 41 are attached to the upper face adjacent the other edge thereof as shown. These metallic strips have tangs 42 struck from their bodies and bent downward into holes 42 formed in the wooden members and 110 standing slightly oblique, and special pins 43 having flat heads 44 are adapted to be passed into the holes in the members, their bodies extending through the holes left in the strips and their heads standing above the 115 work, whether the latter be a quilt or a comfort, so that the same is held firmly on the bars of the frame. If it be a delicate lace curtain which is to be stretched on this frame, the same may be pinned to the fabric 120 strips along its outer edges and its ends. The strips may be carried across the upper edge of the cross bar member if desired, and used when necessary. The operation of forming a quilt or comfort, and the use of 125 this device as a drier for the strips and the like, need not be elaborated in this specification; but it is well known that at times it is desirable to have one side bar move and roll as it moves so that the work can be rolled 130

around it or unrolled from it, and this is obviously accomplished by removing the keys from the holes in the trunnions, rolling the bar and adjusting it, and reinserting the keys. In order to strengthen the parts, the sockets in the blocks may contain metal liners 46, and the trunnions may be round metal rods 47 inserted deeply into sockets in the appropriate ends of the members and secured by transverse pins 49 or other means, the diameter of the rods being such that they will closely fit the lining sleeves and the metal being preferably galvanized so as to prevent rust. This precaution can also be taken with respect to the metal strips and keys and latches, and in fact with respect to all hardware throughout the structure. The outfit will be sold and delivered to the purchaser with appropriate directions for use, and further details are unnecessary in this specification.

What is claimed as new is:—

1. A frame of the class described comprising end bars having longitudinal slots intersected by series of transverse holes, means for supporting said bars, side bars having trunnions projecting axially from their extremities and rotatably and removably mounted in said slots, said trunnions being pierced with transverse holes adapted to align with those in the end bars, and keys for passing through aligned holes.
2. A frame of the class described comprising end bars having longitudinal slots intersected by series of transverse holes, means for supporting said bars, two side bars whereof each is made up of parts hingedly connected and each part has a trunnion projecting axially from its outer extremity, the trunnions pierced with transverse holes adapted to register with those in the end bars when said trunnions extend through the slots of such end bars, extension elements removably mounted on the trunnions for increasing the length of the side bars at will, and means for fastening said elements to the parts of the side bars and to each other and for preventing their rotation on the trunnions.
3. A frame of the class described comprising end bars having longitudinal slots intersected by series of transverse holes, means for supporting said bars, two side bars whereof each is made up of parts hingedly connected and each part has a trunnion projecting axially from its outer extremity, the trunnions pierced with transverse holes adapted to register with those in the end bars when said trunnions extend

through the slots of such end bars, extension elements removably mounted on the trunnions for increasing the length of the side bars at will, each element having pins projecting from one end and sockets in the other end adapted to engage with the pins on the contiguous element for preventing relative rotation, and fastening devices between the elements, for the purpose set forth.

4. In a frame of the class described, the combination with end bars having longitudinal slots, and supports for said bars; of side bars, each made up of a long part and a short part hingedly connected at their meeting ends, the long part having a trunnion projecting axially from its outer extremity and the short part having a long trunnion projecting from its axial extremity and both trunnions having transverse holes, extension sleeves adapted to be strung on the long trunnion for increasing the length of said short part at will, means for fastening the sleeves to each other and to said short part, and keys for engaging said holes and locking the trunnions to the end bars.

5. A side bar member for quilting frames comprising a long part and a short part of rectangular external configuration, the long part having a short trunnion extending axially from its outer end and the short part having a long trunnion extending axially from its outer end, a hinge connecting the inner ends of said parts, latch mechanism for holding said ends together and the parts in alignment, a series of extension elements consisting of blocks of rectangular exterior configuration and provided with axial openings of a size to be strung onto said long trunnion, and interengaging devices between the meeting ends of the blocks and at the outer end of said short part for preventing the relative rotation of elements, the whole for use substantially as described.

6. In a quilting and drying frame, the combination with a pair of end bars, supports therefor, a pair of side bars detachably and adjustably carried by the end bars, and a plurality of extension elements for said side bars; of means for locking all elements together to prevent rotation, fabric strips secured along one edge of the upper face of all elements, and metallic strips secured along the other edge of the same face of all elements and provided with tangs depressed into the elements and producing pin-sockets, for the purpose set forth.

In testimony whereof I affix my signature.

OTTO RACINE.
